UNITED STATES PATENT OFFICE.

JESSE CARL TRIMBLE, OF NORTH OTTER, ILLINOIS.

MAIL-BOX.

1,142,286.

Specification of Letters Patent.

Patented June 8, 1915.

Application filed April 20, 1914. Serial No. 883,271.

To all whom it may concern:

Be it known that I, JESSE C. TRIMBLE, a citizen of the United States, residing at North Otter, in the county of Macoupin and

5 State of Illinois, have invented new and useful Improvements in Mail-Boxes, of which the following is a specification.

My invention relates to improvements in mail boxes, and applies more particularly to 10 mail boxes intended for use in connection with the rural free delivery and parcel post systems.

The principal object of my invention is to provide a mail box which will be inexpensive of manufacture, and efficient in operation, and the design of which will be adapted for use in sheet metal boxes of large 15 dimensions, wherein a rigidity of construction and economical distribution of metal 20 is required.

Another object of my device is to provide effective means for opening and closing the box, allowing the operator to quickly and easily gain admission to the entire floor of 25 the box for the application or removal of packages or mail.

With the above and other objects in view, my invention comprises the new and useful 30 details of construction and arrangement of parts, which will be hereinafter fully described, illustrated in the annexed drawings, and pointed out more specifically in the appended claims.

In the accompanying drawings, wherein 35 the preferred embodiment of my invention is illustrated, like reference characters refer to like or corresponding parts throughout the several views.

Figure 1 is a perspective view of the mail 40 box of my invention, showing the door of the box in its open position. Fig. 2 is a detail perspective view of the latch members shown in their latched relation. Fig. 3 is a sectional view through the wall of my 45 mail box, taken on line 3-3 of Fig. 1, showing the floor in top plan view.

Referring now to the drawings, numeral 1 50 designates the floor of my mail box, which is preferably rectangular in shape, and upon which is mounted the superstructure of the box. The parallel side walls of my box are preferably formed of a single sheet of metal 2, arched over at the top to form a roof, the side walls and roof being supported by 55 angle iron arches 3 and 4, preferably positioned adjacent the ends of the box. The

rear end of the box 5 conforms in shape to the vertical cross section of the box, it being attached to the outer side of the rear arch 3 supporting the superstructure. 60

I have provided the side wall forming sheet 2 of my box to extend beyond the bottom 1, and an inturned flange 6 is provided extending upward for that portion of the walls wherein the walls are parallel, that is to say, the flange extends upward from the floor of the box to the arched portion forming the roof. 65

In the space between flanges 6 and the forward arch 4 is adapted to slide a door 7, 70 parallel forward extending flanges 8 being formed on each of the side edges of the door, which flanges are adapted to slide in the inturned flanges 6 on the side walls of the box. Door 7 conforms in shape to the 75 vertical cross section of the box, the forward arch 4 being adapted to form an obstruction to prevent the door from moving inward out of the slide.

I have provided an over-hanging eave 9 80 on the forward end of my box 2, the eave being formed of an extension of the sheet of metal which forms the side and top. Likewise I provide an out-turned flange 10 on the upper arched edge of the door 7, which 85 flange is adapted to fit snugly beneath eave 9 when the door 7 is in its closed position.

In order to latch the door securely in place, I have provided a spring catch 11, preferably riveted or otherwise attached to 90 the top of the box, a hooked portion of the spring catch being turned downward over eave 9 in position to be engaged by a projecting lip 12 securely attached to the outer face of door 7. It will be readily seen that 95 the over-hanging spring catch 11 will be readily drawn outward to disengage the lip 12 when opening the box. Likewise it will be understood that when the door is forced upward in its slide-way, the lip 12 will 100 readily force the catch 11 forward, allowing the catch to spring backward and engage the lip.

In order to support door 7 when it is lowered to the extreme position of its downward travel, and to prevent the door from falling away from the box, I have provided a metal strip 13 bridging between the side walls across the forward end of the box at the bottom thereof. Strip 13 is positioned 110 to engage the lip 12 to prevent the door from traveling farther downward.

From the foregoing description it will be readily seen that my invention provides an inexpensive mail box, which will be simple in operation, and effective in design, and 5 which design will provide a rigid construction and an economical distribution of metal.

While I have herein described and illustrated the preferred embodiment of my invention, I do not wish to be limited strictly 10 to the details shown, as it is obvious that the arrangement and construction may be varied in many ways, without departing from the broad spirit of my invention.

Having thus described my invention, what 15 I claim is:—

1. In a mail-box, a body having a bottom, sides, top, back and an open front, a door vertically slidable across the open front, a spring catch member fixed to the top and 20 having a hooked portion over-hanging the

top, and a projecting lip fixed to the door and positioned to be engaged by the hooked portion of the spring catch to lock the door in its closed position.

2. In a mail-box, a body having a bottom, 25 sides, top, back and an open front, a door vertically slidable across the open front, a projecting lip on said door adjacent the top thereof, a horizontal strip across the open front of the box forward of the door and adjacent the bottom of the box, and said horizontal strip positioned to engage the projecting lip on the door to prevent the door from falling away from the box when in its open position.

JESSE CARL TRIMBLE.

Witnesses:

J. C. TRIMBLE.

Copies of this patent may be obtained for five cents each, by addressing the "Commissioner of Patents, Washington, D. C."

It is hereby certified that in Letters Patent No. 1,142,286, granted June 8, 1915, upon the application of Jesse Carl Trimble, of North Otter, Illinois, for an improvement in "Mail-Boxes," an error appears in the printed specification requiring correction as follows: Page 1, line 5, before the word "have" insert the words *whose post-office address is Girard, Illinois*; and that the said Letters Patent should be read with this correction therein that the same may conform to the record of the case in the Patent Office.

Signed and sealed this 27th day of July, A. D., 1915.

[SEAL.]

R. F. WHITEHEAD,
Acting Commissioner of Patents.
